UNITED STATES PATENT OFFICE

NORA L. SHANKLAND, OF NEWTON, IOWA

WINDOW STOP

Application filed May 31, 1929. Serial No. 367,394.

Reference is made to my former patent for window stop, numbered 1,461,499, dated July 10, 1923, of which this is an improvement.

5 An object of this improvement is to add a sash-plate attachment which is morticed into the sash. The assembled construction will make the stop less conspicuous from the outside and therefore neater in appearance.

10 Another object of my present invention is the provision of a window fastener which is rustless, durable, certain of operation, and inexpensive to manufacture.

With the preceding and other objects and 15 advantages in mind, the invention consists in the novel combination of elements, construction and arrangement of parts and operations to be hereinafter more fully described, claimed and illustrated in the accompanying drawing, wherein:

Figure 1 is a perspective view of the window stop or fastener attached thereto;

Fig. 2 is a side elevation of the fastener in locked position;

25 Fig. 3 is a horizontal cross-sectional view taken on line 3—3 of Fig. 2;

Fig. 4 is a similar cross-sectional view showing the fastening device unlocked, and

30 Fig. 5 is a vertical cross-sectional view taken on line 5—5 of Fig. 2.

Referring in detail to the drawing wherein similar characters of reference designate the same parts in the several views, the numeral 1 shows a frame of which 2 is the 35 upper sash and 3 is the lower sash.

In the upper sash 2 is a mortice portion or recess 4 which has a metal lining 5 held positioned by screws 6. One portion of a hinged locking device is 7, the other section 40 is 8, the two being connected by pintle or hinge-pin 9.

Section 7 is fastened to sash 2 by screws

45 10. A transverse channel 11 is formed in section 7 while 12 is a locking bolt provided with slot 13 which is attached to member 8 by pin 14, both provided with finger engaging means 15.

A keeper 16 is provided with a transverse channel 17 and attached to the lower sash 50 3 by screws 18.

The construction is easily morticed into the frame and not visible from the outside.

In unlocked position member 8 is folded back on section 7 within the morticed recess 4. In locked or fastened position the lower 55 edge of 8 engages channel 17 of the keeper 16 thereby preventing the lower sash 3 from being raised.

In locked position the locking bolt 12 is slid into channel 11 holding the hinged portions 7 and 8 closed. When unlocked the bolt 12 may be positioned longitudinally 60 with hinged position 8 thereby being out of the way.

The device is simple to operate, fool-proof, 65 neat, inexpensive and efficient in operation.

It is understood that the form of my invention herein shown and described is to be taken as a preferred example of the same, and that various changes in the shape, size 70 and arrangement of parts may be resorted to without departing from the spirit of the invention or the scope of the subjoined claim.

Having thus described my invention, what 75 I claim as new and desire to secure and protect by Letters Patent of the United States, is:

A window-stop comprising a pair of hingedly connected plates, one of said plates 80 being rigidly attached within a mortised recess of one sash of a window, a keeper attached to the other sash of a window, the keeper provided with a transverse channel, said channel being adapted to be engaged by 85 the opposed hinged plate, and a bolt slidably and pivotally connected to the second mentioned hinged plate, adapted to hold the hinged plates in locked position.

Mrs. NORA L. SHANKLAND. 90
